ART OF MAKING CASTINGS.

1,013,548.

Specification of Letters Patent.

Patented Jan. 2, 1912.

Application filed September 25, 1911. Serial No. 651,047.

To all whom it may concern:

Be it known that I, CHARLES M. GREY, a citizen of the United States, residing in East Orange, county of Essex, and State of New Jersey, have invented certain new and useful Improvements in the Art of Making Castings, of which the following is a specification.

This invention is a process of making castings, and while it is capable of quite general application it is of special advantage and utility in making die castings, and I will particularly describe its application to this latter art.

Several processes are in use for making die castings the aim of all of which is to produce solid castings, *i. e.*, castings free from blow holes and entrained gases, and, also, castings which are uniform in weight and size. The processes in use involve such expedients as forcing the metal into the die by pressure, producing a partial vacuum in the die, etc. Moreover, in most of the commercial processes of the prior art employing a vacuum in the die, a valve is used to control the flow of molten metal to the die, with the result that the metal frequently "freezes" around the valve, or its associated mechanism, thereby rendering the valve defective and precluding the production of good castings. None of the processes heretofore used, produce uniform solid castings, and, as a result, die castings have not gone into such extensive use as experts in the art predicted.

The present process is not only simple and economical, but results in castings which are exceptionally solid, uniform and accurate, and entirely free from the defects heretofore existing in die castings.

With the specified objects in view, the invention, in one of its broadest aspects, embodies a method of controlling the flow of molten metal to the mold or die. This method consists in confining the metal in two chambers or compartments which communicate only beneath the surface of the metal, one of the chambers being connected with the die or mold space, producing a partial vacuum of the same degree in the two chambers whereby the metal is restrained from flowing toward the die, *i. e.*, retaining it in a balanced condition, and, when it is desired to cause the metal to flow into the die, changing the relative pressure

in two chambers, preferably by increasing the pressure in the chamber not directly connected with the die, whereby the metal is forced into said die.

The process consists further in combining the foregoing operation or operations with the step of simultaneously producing a vacuum in the die and also in the passage connecting the metal chamber with the die, whereby, when pressure is applied to the metal chamber not directly connected with the die, the metal is quickly and forcibly ejected into the mold as a result of the vacuum forwardly of the metal and the die, and the pressure rearwardly of the metal. It is apparent, therefore, that a valve is not required to control the flow of metal from the metal chamber to the die. The pressure employed may be produced by mechanical appliances, such as those heretofore employed in this art, though for simplicity and effective operation I prefer to employ fluid pressure produced by compressed air.

Looking at the process in a more detailed and specific aspect, particularly with respect to the type of apparatus illustrated and described herein for practicing the invention, said process consists in confining the molten metal in a substantially U-shaped, or equivalent, receptacle having two communicating chambers or compartments, the communication between which is sealed by the fused metal, one of said chambers having unobstructed communication with the die; exhausting the air from the die and the communication between the die and the said metal chamber, and simultaneously exhausting the air from the other metal chamber whereby a partial vacuum is produced forwardly of the metal, *i. e.*, in the passage leading therefrom to the die as well as in the die, and, also, in the metal chamber not directly connected with the die, thereby restraining the metal from flowing toward the die; then, while maintaining the vacuum in the die and passage leading thereto, applying fluid pressure on the surface of the metal in the chamber not directly connected with the die, whereby the metal is quickly and forcibly advanced into said die.

Other features of the invention and the advantages thereof, not heretofore adverted to, will be obvious from the following detailed description of the practical way of carrying out the process.

In the accompanying drawing I have illustrated an apparatus, somewhat diagrammatically, which I have found suitable for practicing the process, but it will be understood that such apparatus is merely illustrative of a type of apparatus which may be employed, and not in any manner exclusive. The said drawing shows a longitudinal sectional view of the apparatus, 10 with the pipe connections in elevation.

Referring to the drawing A is the molten metal receptacle, which may be positioned in a suitable heating furnace B. Receptacle A, which is shown as substantially U-shaped, has two compartments or chambers a and b, respectively, said chambers having a connection near their lower ends which is normally sealed by molten metal c in the receptacle A. A space d is left in chamber a 15 above the metal, and a corresponding space e is left in chamber b above the metal.

C is a die or mold, of usual type, having an upper member f and lower member g, the die or mold space h being positioned between said members. The mold C is positioned on a supporting member i, and an inlet or passage k is provided in the lower member g whereby metal may be introduced into said mold, said passage k connecting 25 through an opening in base member i with space e in the upper part of chamber b. The mold or die space h is provided with the customary air ducts l leading therefrom to a common chamber, from which chamber extends an exhaust pipe n. Exhaust pipe n is connected with a suitable pump or exhausting mechanism D, whereby air may be exhausted from the mold or die and, also, from the space e in the upper part of chamber b, thereby producing a partial vacuum 30 in space e and mold space h.

E is a pressure regulator, of well known type, consisting of a two part casing, the said parts being lettered o and p, respectively, and positioned between which is a diaphragm q providing a chamber r on one side thereof, and a corresponding chamber s on the opposite side. Two valve rods, t and v, respectively, are secured to the diaphragm, 45 rod t connecting with and operating a valve t' working in valve casing t² positioned in pipe n. Valve rod v is connected with and operates valve v' working in valve casing v², positioned in pipe c' which establishes communication between a pipe c² and the exhaust device D. Pipe c' is provided with a valve c³ the function of which will be presently described. Pipe c² connects the space d in the upper part of chamber a with the 50 exhaust device D through the intermediate pipe connection c'. Forming an extension of the pipe c² is a pipe d', connected with a source of compressed fluid, not shown, said pipe d' being provided with a valve d². 55 A by-pass, e', extends from pipe n, at a

point above the valve therein, to the chamber r on one side of diaphragm q, and a corresponding by-pass e² extends from the pipe c', at a point above the valve therein, to space s on the opposite side of the diaphragm, the function of all of which will be hereafter described. 70

A pressure relief valve is shown at f'.

Having described an apparatus which may be used in carrying out the process its 75 operation will be readily understood, and may be described, briefly, as follows: Assuming the mold C is properly prepared for casting, and the furnace A contains molten metal, the exhausting apparatus D is put 80 into operation. This results in the production of a partial vacuum in chamber e, metal passage k, and mold space h, through exhaust pipe n connected with the exhaust and, also, in the simultaneous production of 85 a partial vacuum in chamber d through exhaust pipes c' and c². The partial vacuum is of the same degree in chamber d as it is in chamber e and mold space h, and this condition is effected by the pressure regulator 90 E, the operation of which will be briefly described. The suction apparatus D, at the commencement of the exhausting operation, exhausts equally through pipes n and c², but if at any time the degree of vacuum becomes 95 greater in one pipe than in the other, e. g., greater in pipe n leading from the chamber e and mold space h than in pipe c² leading from chamber d, the excess pressure in pipe c² would be communicated to diaphragm q through by-pass e², thereby forcing the valve t' to its seat and permitting the entire suction of apparatus D to be exerted on pipe c², through the medium of pipe c'. This condition continues until the 100 vacuum in chamber d and pipe c² equals that in chamber e. The by-pass e' operates in a corresponding manner to by-pass e². The diaphragm of the regulator, therefore, pulsates back and forth, in accordance with 105 the slight variation in vacuum in the two lines of pipe n and c², the result being that the same degree of vacuum is produced in chamber d as in chamber e and mold space h. The effect of producing a vacuum of 110 the same degree in chambers d and e, and mold space h, is to restrain the metal from flowing into the die, i. e. to hold said metal in a balanced condition or state of equilibrium. When the vacuum has reached the 115 degree desired, i. e., when the air is sufficiently exhausted from the die space h, and it is desired to force the metal into said die space, valve c³ is closed and valve d² 120 simultaneously opened, thereby allowing compressed fluid, e. g., compressed air, to enter pipe c² and exert its pressure on the surface of the metal in chamber d. As the suction continues through pipe n, the molten metal is quickly and forcibly shot into the 125 130

die, completely filling it, and producing a firm, solid casting, and one entirely free from blow holes or entrained gases.

It will be understood, of course, that a plurality of castings may be made simultaneously, and that the described operation of the apparatus may be repeated by a simple manipulation of the proper valves.

Particular attention is called to the fact that the castings are made under most favorable conditions of operation, so far as concerns precluding the formation of air or gas holes in the castings, and that this result is secured without clogging up any valves or other parts of the apparatus. Applying suction to both surfaces of the metal prior to casting frees it from all entrained air and gases, and should any air work down into the molten metal, as the result of applying air pressure to the surface of the metal in chamber *d*, this would be subsequently removed by the exhaustion incident to preparing for another casting operation.

Prior to opening the mold *C* to take out the casting, the air pressure will be shut off by closing valve *d*², and the pressure in pipe *c*² and chamber *a* may be relieved, and normal atmospheric pressure restored therein, by opening valve *f*.

It will be understood that the process described may be modified as to details, such as the substitution of equivalents, and that one or more steps of the process may be employed without necessarily using the complete process.

Having thus fully described the invention, what I claim as new, and desire to secure by Letters Patent is:—

1. In the art of making castings, the process which consists in confining fluid material in two chambers having communication beneath the surface of said material, and producing a partial vacuum in the said two chambers above the metal therein by exhausting air from both of said chambers.

2. In the art of making castings, the process which consists in confining fluid material in two chambers having communication beneath the surface of said material, producing a partial vacuum in the said two chambers above the metal therein by exhausting air from both of said chambers, and then introducing the material into a mold.

3. In the art of making castings, the process which consists in confining fluid material in two chambers having communication beneath the surface of said material, producing a partial vacuum in the said two chambers above the metal therein by exhausting air from both of said chambers, and then introducing the material into a mold by changing the relative pressures in the two chambers.

4. In the art of making castings, the process which consists in confining fluid material

in two chambers having communication beneath the surface of said material, producing a partial vacuum in the said two chambers above the metal therein, and then introducing the material into a mold by applying pressure interiorly of one of the chambers.

5. In the art of making castings, the process which consists in confining fluid material in two chambers having communication beneath the surface of said material, producing a partial vacuum in the said two chambers above the metal therein, and then introducing the material into a mold by applying pressure interiorly of one of the chambers while continuing suction on the other.

6. In the art of making castings, the process which consists in confining fluid material in two chambers having communication beneath the surface of said material, producing a partial vacuum in the said two chambers above the metal therein by exhausting air from both of said chambers, and then introducing the material into a mold by applying gaseous pressure interiorly of one of the chambers.

7. In the art of making castings, the process which consists in confining fluid material in a receptacle having two chambers communicating beneath the surface of the material, connecting one of said chambers with a mold through an unobstructed passage, producing a partial vacuum in both chambers, in the mold, and in the said passage, and then forcing the material into the mold by applying pressure to the metal in the chamber not connected with said passage.

8. In the art of making castings, the process which consists in confining fluid material in a receptacle having two chambers communicating beneath the surface of the material, connecting one of said chambers with a mold through an unobstructed passage, producing a partial vacuum in both chambers, in the mold, and in the said passage by exhausting air from both of said chambers, and then forcing the material into the mold by applying gaseous pressure to the metal in the chamber not connected with said passage.

9. In the art of making casting, the process which consists in confining fluid material in a receptacle having two chambers communicating beneath the surface of the material, connecting one of said chambers with a mold through an unobstructed passage, producing a partial vacuum in both chambers, in the mold, and in the said passage, and then forcing the material into the mold by applying pressure to the metal in the chamber not connected with said passage while continuing suction on the mold.

10. In the art of making castings, the process which consists in confining fluid material in a receptacle having two chambers communicating beneath the surface of the

material, connecting one of said chambers with a mold through an unobstructed passage, exhausting air and gases directly from one of said chambers, exhausting air and gases from the other chamber through the mold whereby substantially the same degree of vacuum is produced in the two chambers and the mold, and then relieving the suction on the chamber not connected with the mold 10 whereby the same is placed under atmospheric pressure and the material forced into the die.

11. In the art of making castings, the process which consists in confining fluid material in a receptacle having two chambers communicating beneath the surface of the material, connecting one of said chambers with a mold through an unobstructed passage, exhausting air and gases directly from 15 one of said chambers, exhausting air and gases from the other chamber through the mold whereby substantially the same degree of vacuum is produced in the two chambers and the mold, and then applying gaseous 20 pressure to the chamber not directly connected to the mold, whereby the material is 25 forced into the mold.

12. The process of making die castings which consists in confining molten metal in 30 two chambers having communication beneath the surface of the metal and one of which is connected with a die, producing a partial vacuum of substantially the same degree in both of said chambers and also in the 35 die whereby the metal is restrained from entering the die, and then applying pressure to the metal in the chamber not directly connected with the die whereby the metal is forced into the die.

40 13. The process of making die castings which consists in confining molten metal in a substantially U-shaped receptacle, connecting the top of one leg of said receptacle with a die, producing a vacuum of substantially the same degree in both legs of said 45 receptacle and in the die, and then applying gaseous pressure to the surface of the metal in that leg of the receptacle not directly connected with the die.

14. In the art of making castings, the process which consists in confining fluid material in two chambers having communication beneath the surface of said material, producing a partial vacuum in the said two chambers above the metal therein while precluding any flow of metal toward the mold, 50 and then introducing the material into a mold.

15. In the art of making castings, the process which consists in confining fluid material in two chambers having communication beneath the surface of said material, producing a partial vacuum in the said two chambers above the metal therein while precluding any flow of metal toward the mold, 55 and then introducing the material into a mold by changing the relative pressures in the two chambers.

16. In the art of making castings, the process which consists in confining fluid material in two chambers having communication beneath the surface of said material, producing a partial vacuum in the said two chambers above the metal therein while precluding any flow of metal toward the mold, 60 and then introducing the material into a mold by changing the relative pressures in the two chambers.

17. In the art of making castings, the process which consists in confining fluid material in a receptacle having two chambers communicating beneath the surface of the material, connecting one of said chambers with a mold through an unobstructed passage, producing a partial vacuum in both 85 chambers, in the mold, and in the said passage, while precluding any flow of metal toward the mold, and then forcing the material into the mold by applying gaseous pressure to the metal in the chamber not 90 connected with said passage.

In testimony whereof I have signed my name to this specification in the presence of two subscribing witnesses.
